DAVID HAIN, HENRY A. GROSS, AND MARTIN HAIN, OF THE COUNTY OF GASCONADE, MISSOURI.

Letters Patent No. 65,806, dated June 18, 1867.

IMPROVEMENT IN SORGHUM-STRIPPER.

The Schedule referred to in these Letters Patent and making part of the same.

TO ALL WHOM IT MAY CONCERN:

Be it known that we, DAVID HAIN, and HENRY A. GROSS, and MARTIN HAIN, of the county of Gasconade, and State of Missouri, have invented a new and useful "Sorghum-Stripper;" and we do hereby declare that the following is a full and clear description thereof, reference being had to the accompanying drawings and to the letters of reference marked thereon.

Figure 1, of the drawings, is a front elevation of the improved machine.

Figure 2 is a plan of the same.

The object of this invention is to produce a machine that is capable of stripping the leaves from the stalks of sorghum in a very rapid and perfect manner, preparatory to passing the said stalks through a crushing machine.

To enable those skilled in the art to make and use our improved machine, we will proceed to describe its construction and operation.

A is a frame resting upon its legs *a*, used for the support of the other parts of the machine. B is a face-plate, of either metal or wood, fastened to the frame A. This construction is probably the most simple for a perfect machine; but for a rudely constructed machine, embracing the same general features as the subject of the present description, the frame A may be dispensed with and the face-plate B temporarily secured to some portion of a building or even to posts temporarily set in the ground. There are to be two or more knife-handles, C *c*, fastened to the face-plate B in a permanent manner, as shown in fig. 1, and extending upward at an angle of about forty-five degrees (more or less) from the top plane of the face-plate. The top ends of these knife-handles are provided with small knives, *c*², semi-elliptical in form, and of such a size as to embrace about one-half of an ordinary stalk of the cane or sorghum. There are two or more other knife-handles, C¹ *c*¹, pivoted to the face-plate at *x*, and, like the handles C *c*, provided with knives *c*³, similar in size and form to the knives *c*². The knives *c*³ are arranged to shut down on top of the knives *c*², and the two together form, when closed, an elliptical opening between them, for the admission of the stalk to be stripped. One pair of the knife-handles should be placed before the plate B and the other pair behind it, so that the front pair of knives will strip off any leaves that might be left in the stalk by passing through that portion of the opening between the other knives in which they do not close upon the stalk. The lower ends of the handles C¹ extend below the plate B sufficiently to be pivoted at *x*¹ to the toggle bars D. These toggle bars are pivoted or hinged together, and to the vertical rod D¹, at *x*². The spring D², attached to the upper end of the rod D¹, draws the two adjacent ends of the bars D up tightly to the bottom side of the plate B, and in this position they act upon the knife-handles C¹ like a toggle-joint, to hold them firmly in position at their lower ends. The treadle D³ is connected by means of the link *d* with the bars D at *x*², and the foot of the operator pressed down upon the said treadle will depress the inner ends of the bars D and cause them to draw the two lower ends of the handles C¹ towards each other, thereby opening the knives *c*³ from the knives *c*² so as to permit the stalk to be stripped to be laid on top of the knives *c*². There may be a rest, E, at some distance from the knives, so as to hold up the outer end of the stalk when it is first placed upon the knives, preparatory to being stripped of its leaves. The stalk to be stripped is to be placed with its smaller end between the knives *c*² *c*³, and then drawn forward through between the knives, which will be closed upon it as soon as the treadle is released. The knife-handles at *c* and *c*¹ should be made flexible, so as to allow them to spring apart sufficiently to accommodate the increased size of the stalk as it is drawn forward. In lieu of the spring D the lever F and weight F¹ may be employed, as shown in fig. 1, for the purpose of raising up the inner ends of the bars D. This machine may be constructed wholly of metal, or it may be constructed of wood with the exception of the knives *c*² *c*³.

Having described our invention, what we claim is—

1. Two pair of semi-elliptical knives, *c*² *c*³, one pair of which is to be placed in front of the other, substantially as described and set forth.
2. We claim the flexible handles *c* *c*¹, in combination with the knives *c*² *c*³, for the purpose of allowing the said knives to yield readily to any variation in the size of the stalk passed between them.
3. We claim the knife-handles C¹ and the toggle bars D, when combined as herein described and set forth for the purpose, opening or raising the knives *c*³.
4. We claim the knife-handles C¹, the toggle bars D, the spring D² or its equivalent, the rod D¹, the link *d*, and the treadle D³, when constructed and arranged substantially as herein described and set forth.
